US00D699348S

(12) **United States Design Patent**
Morejon

(10) **Patent No.:** **US D699,348 S**
(45) **Date of Patent:** **** Feb. 11, 2014**

(54) **HANDLE**

(76) Inventor: **Orlando Morejon**, Key Largo, FL (US)

(**) Term: **14 Years**

(21) Appl. No.: **29/387,261**

(22) Filed: **Mar. 10, 2011**

Assistant Examiner — Carissa C Fitts

(74) *Attorney, Agent, or Firm* — Malloy & Malloy, P.L.

(57) **CLAIM**

The ornamental design for a handle, as shown and described.

DESCRIPTION

FIG. 1 is a bottom perspective view illustrating my design for a handle;

FIG. 2 is a top perspective view thereof;

FIG. 3 is a top elevational view thereof;

FIG. 4 is a right side view thereof;

FIG. 5 is a bottom elevational view thereof;

FIG. 6 is a left side view thereof;

FIG. 7 is a rear view thereof; and,

FIG. 8 is a front view thereof.

1 Claim, 3 Drawing Sheets
